P. R. FORTIN

RELAY

Filed June 9, 1922

Fig. 1.

Inventor:
Paul R. Fortin,
Albion, New
Hampshire

UNITED STATES PATENT OFFICE.

PAUL R. FORTIN, OF SCHENECTADY, NEW YORK, ASSIGNOR TO GENERAL ELECTRIC COMPANY, A CORPORATION OF NEW YORK.

RELAY.

Application filed June 9, 1922. Serial No. 567,065.

To all whom it may concern:

Be it known that I, PAUL R. FORTIN, a citizen of the United States, residing in Schenectady, in the county of Schenectady, 5 State of New York, have invented certain new and useful Improvements in Relays, of which the following is a specification.

My present invention relates to relays, and more particularly to relays of the type 10 which are adapted to be operated by weak currents such as those employed for signaling purposes.

The object of my invention is to provide a relay structure which is capable of being 15 operated reliably by very small currents, and which is also capable of very fine adjustment.

The novel features which I believe to be 20 characteristic of my invention are set forth in the appended claims. My invention itself, however, both as to its organization and method of operation will best be understood by reference to the following description taken in connection with the accompanying drawing in which Fig. 1 is a 25 front elevation, and Fig. 2 is a side elevation of a relay constructed in accordance with my invention.

As indicated in the drawing the relay 30 comprises an electromagnet 1, having a yoke 2 and an armature 3 which is pivoted at 4. The electromagnet is supported on the yoke 2 by means of a threaded core extension and a cooperating nut 2' and by means 35 of the screws 5 upon a supporting member 6 which in turn is secured to a base by means of the screws 7. Two spring contact members 8 and 9 are also supported on the supporting member 6 by means of the screws 40 10 being insulated from the support and from each other by means of the spacing members 11, 12 and 13. These spring contact members may be connected in any suitable way to the circuit which is to be controlled by the relay. The armature 3 of 45 the electromagnet 1 acts through the pin 14 upon the spring contact member 8, to open the contact at 15 when the armature is actuated.

50 Separate means is provided for adjusting each of the spring contact members 8 and 9. Spring contact member 9 is relatively stiff with respect to the member 8, and is provided with a separate reinforcing strip 16

extending parallel therewith. The adjusting screw 17 which passes through the support 6 and is suitably insulated therefrom, bears upon the spring contact member 9 and presses it together with the separate reinforcing strip 16, away from the contact member 8. This provides a coarse adjustment of the pressure between the two contact springs. The spring contact member 8 is provided with a separate fine adjustment which comprises a separate reinforcing spring 18 extending parallel thereto, as indicated, and a spring member 19 which extends at a right angle to the other contact springs and which is supported by means of the screw 20 from the supporting member 6. The adjusting screw 21 bears upon the free end of the spring 19 and the spring 19 bears upon the pin 22, which is secured to contact spring member 8. A small movement of the screw 21 produces 75 a much smaller movement of the pin 22 and of the spring contact member 8 and its reinforcing spring 18. In this way a very delicate adjustment of the spring contact member 8 may be made both for adjusting its pressure upon the spring contact member 9, and also for adjusting the relation of the pin 14 to the armature 3 to insure the desired operation of the relay. Spring stop members 23 are provided which 80 bear against the knobs of the screws 17 and 21 to prevent them from being accidentally turned after the relay has once been adjusted.

A relay such as I have described is 90 adapted to a wide variety of uses. As one example of such use I have found that it is well adapted for the control of the operation of a radio transmitting set by means of small alternating current or interrupted 95 direct current impulses transmitted from a distance to the actuating coil 1 over an ordinary telephone line.

While I have shown and described the 100 preferred embodiment of my invention it will be apparent that my invention is by no means limited to the precise structural arrangement shown and described, but that many modifications in the relation of the 105 different parts of the relay and of their form may be made without departing from the scope of my invention as set forth in the appended claims.

What I claim as new and desire to secure by Letters Patent of the United States, is:—

1. The combination in a relay of an electromagnet, an armature controlled thereby, 5 a pair of substantially parallel spring contact members one of which is adapted to be moved by the movement of said armature, a common support for said contact members and independent means for adjusting each of 10 said spring contact members.
2. The combination in a relay of an electromagnet, an armature controlled thereby, a pair of spring contact members one of which is more flexible than the other and one of 15 which is adapted to be moved by the movement of said armature and independent means for adjusting each of said spring contact members.
3. The combination in a relay of an electromagnet, an armature controlled thereby, 20 a pair of spring contact members, one of which is adapted to be moved by the movement of said armature and independent means for adjusting each of said spring contact members, one of said adjusting means being adapted to provide a finer adjustment than the other.
4. The combination in a relay of an electromagnet, an armature controlled thereby, 30 a pair of spring contact members, one of which is more flexible than the other, and one of which is adapted to be moved by the movement of said armature, and independent means for adjusting each of said spring 35 contact members, the adjusting means for the more flexible member being adapted to provide a finer adjustment than the other.
5. The combination in a relay of an electromagnet, an armature controlled thereby, 40 a pair of spring contact members one of which is more flexible than the other, means whereby the more flexible member may be moved by the movement of said armature and independent means for adjusting each of 45 said spring contact members.
6. The combination of a relay of an electromagnet, an armature controlled thereby, a pair of spring contact members one of which is more flexible than the other, means 50 whereby the more flexible member may be moved out of contact with the other by the movement of said armature and independent means for adjusting each of said spring contact members.
7. The combination in a relay of an electromagnet, an armature controlled thereby, a pair of spring contact members one of which is more flexible than the other, means 55 whereby the more flexible member may be moved by the movement of said armature and independent means for adjusting each of said spring contact members, one of said adjusting means being adapted to provide a finer adjustment than the other.
8. The combination in a relay of an elec- 60
- tromagnet, an armature controlled thereby, a pair of spring contact members one of which is more flexible than the other, means whereby the more flexible member may be moved by the movement of said armature, an independent means for adjusting each of said spring contact members, the adjusting means for the more flexible member being adapted to provide a finer adjustment than the other. 70
9. The combination in a relay of an electromagnet, an armature controlled thereby, a pair of spring contact members one of which is more flexible than the other, means whereby the more flexible member may be moved by the movement of said armature, an adjusting screw which acts directly upon the stiffer member and a separate adjusting screw which acts upon the more flexible member through a separate adjustment spring. 80
10. The combination in a relay of an electromagnet, an armature controlled thereby, a pair of spring contact members one of which is more flexible than the other, means whereby the more flexible member may be moved by the movement of said armature, an adjusting screw which acts directly upon the stiffer member and a separate adjusting screw which acts upon the more flexible member through a separate adjustment spring. 85
11. The combination in a relay of an electromagnet, an armature controlled thereby, a pair of spring contact members one of which is more flexible than the other, means whereby the more flexible member may be moved by the movement of said armature, an adjusting screw which acts directly upon the stiffer member and a separate adjusting screw which acts upon the more flexible member through a separate adjustment spring extending at a right angle thereto. 90
12. The combination in a relay of an electromagnet, an armature controlled thereby, a pair of spring contact members one of which is more flexible than the other, means whereby the more flexible member may be moved by the movement of said armature, an adjusting screw which acts directly upon the stiffer member and a separate adjusting screw which acts upon the more flexible member through a separate adjustment spring extending at a right angle thereto, and separate reinforcing members which coact with each of said spring members and with the adjusting means therefor. 100
13. The combination in a relay of an electromagnet, an armature controlled thereby, a pair of spring contact members one of which is more flexible than the other, means whereby the more flexible member may be moved by the movement of said armature, an adjusting screw which acts directly upon the stiffer member and a separate adjusting screw which acts upon the more flexible member through a separate adjustment spring extending at a right angle thereto, and separate reinforcing members extending parallel with and which coact with each of said spring members and with the adjusting means therefor. 105
14. The combination in a relay of an elec- 110
- tromagnet, an armature controlled thereby, a pair of spring contact members one of which is more flexible than the other, means whereby the more flexible member may be moved by the movement of said armature, an adjusting screw which acts directly upon the stiffer member and a separate adjusting screw which acts upon the more flexible member through a separate adjustment spring extending at a right angle thereto, and separate reinforcing members extending parallel with and which coact with each of said spring members and with the adjusting means therefor. 115
15. The combination in a relay of an elec- 120
- tromagnet, an armature controlled thereby, a pair of spring contact members one of which is more flexible than the other, means whereby the more flexible member may be moved by the movement of said armature, an adjusting screw which acts directly upon the stiffer member and a separate adjusting screw which acts upon the more flexible member through a separate adjustment spring extending at a right angle thereto, and separate reinforcing members extending parallel with and which coact with each of said spring members and with the adjusting means therefor. 125

In witness whereof, I have hereunto set my hand this 8th day of June, 1922.

PAUL R. FORTIN.
